REED MOTION CONTROL FOR TERRY LOOM
Edward L. Carter, Kannapolis, N.C., assignor to Cannon
Mills Company, Kannapolis, N.C., a corporation of
North Carolina

Filed June 14, 1963, Ser. No. 287,989
9 Claims. (Cl. 139—27)

The present invention relates to a reed motion control for a loom for weaving terrycloth, and to such a reed motion control which has as a part thereof a center reed lock control.

In the weaving of terry fabric, the reed of the loom is caused to beat up the filling only on certain picks of the loom. For example, three picks of filling may be laid in the cloth, at a distance of about one-fourth to three-eighths of an inch from the fell of the cloth, and the reed, instead of being caused to beat up on each pick, as in an ordinary loom, is prevented from beating up by being swung back away from the fell of the cloth by a reed motion control. After the third pick, the ground warp is held tight, and at the same time a predetermined amount of pile warp is let off. The reed motion control is then actuated so as to hold the reed in the forward position, i.e. it does not swing the reed back, and the normal forward movement of the lay, on which the reed is mounted, causes the picks to be beat up and the pile warps to be looped out on opposite sides of the cloth, thereby forming the terrycloth.

The usual way of controlling the reed motion is by means of a cam device which is usually positioned under the loom, often at the back of the loom, and which device has a cam shaped so that at the speed at which the cam is driven, it will act to swing the reed back for two picks and then to hold it forward on the third pick. While such cam devices give a positive control over the reed motion, they are otherwise subject to disadvantages in that they are usually quite heavy and therefore add to the weight of the loom and use up power during their operation, and in that they are rather difficult to adjust, both because of their position, and because of the fact that the cam surface is permanent and adjustments to adjust the swing of the reed must be made in the linkage between the cam and the reed. A further and more serious drawback is that if it is desired, for example in order to weave a different type of terrycloth such as a cloth in which all the loops are on one side of the cloth or in which the picks between beat up movements are greater in number than three, the entire cam mechanism together with the gearing driving it must be changed over. In addition, when it is desired to disengage the reed motion control so that the reed beats up on each pick in order to weave in the ordinary manner, which is often necessary in weaving towels of terrycloth, this must usually be done by disengaging a pin or key from the linkage at a point between the cam control and the rest of the linkage. The disengagement almost always occurs at a time when there is a strain on the linkage, and as a result the pins or keys wear out frequently and must be replaced. Due to the position of the cam mechanism under the loom, this requires a great amount of effort and is time consuming, thereby resulting in expensive "down time" for the loom. The cumulative effect of such "down time" for looms in a large mill can become very great.

Efforts have been made to solve these problems, but they have been mainly in the direction of simply increasing the number of cams to provide flexibility in operation and providing means for switching over from one cam to the other during operation. Insofar as maintenance and adjustment of the loom and economy in loom manufac-

2

ture and operation are concerned, such solutions have only caused problems to multiply.

5 The present invention has as an object the provision of a simple reed motion control which eliminates the necessity for a cam mechanism, and which provides a simple control of the reed motion which is easily accessible on the loom and is easily adjustable.

10 A further object of the present invention is the provision of a reed motion control which is light in which and which is inexpensive both to manufacture and to maintain.

15 A still further object of the invention is the provision of a reed motion control which provides a wide range of adjustments for the reed motion, and by means of which the timing of the reed motion can be changed easily and quickly.

20 Other and further objects of the present invention will become apparent from the following specification and claims, taken together with the accompanying drawings, in which:

FIG. 1 is front perspective view of a terry loom according to the present invention showing only the parts with which the present invention is concerned;

25 FIG. 2 is an enlarged sectional view along line 2—2 of FIG. 1 showing the reed in the beat up position;

FIG. 3 is a view similar to FIG. 2 in which the reed is in the swung back position;

FIG. 4 is an enlarged perspective view of the lower portion of the loom showing the reed motion control in detail;

FIG. 5 is a fragmentary sectional view of a center reed lock motion according to the present invention; and

FIG. 6 is a front elevation view of the lock motion of FIG. 5.

30 Referring to FIGS. 1-3, the loom lay 10 has a reed 11 pivoted on studs 15 at the ends of the reed cap 14, the reed 11 being held in the reed cap, reed hangers 13 and the reed bed 12. A typical linkage for swinging the reed 11 counterclockwise in FIGS. 2 and 3 away from the fell of the cloth (not shown) which is to the left in the figures is provided at each end of the reed. The linkage comprises a reed frame arm 16 on the reed, having one end of a reed motion toggle 17 pivoted thereto. The other end of the toggle 17 is pivoted to the lay 10, and the two links of the toggle are pivoted to each other at a center pivot 18. A locking spring 19 is connected between the said other end of the toggle 17 and the frame of the loom and tends to pivot the toggle 17 past the dead center position as shown in FIG. 2, in which position the reed is in the fully beat up position.

35 Pivoted to the center pivot 18 is a reed motion link 23 having the other end slidably linked to a reed motion crank 22 which is fixed on a reed motion shaft 20 by means of set screws 22a. Shaft 20 is mounted in self aligning bearings 21.

40 In operation, when the picks are to be beat up to the fell of the cloth, the reed motion shaft is rotated to the position shown in FIG. 2, in which the reed motion cranks 22 raise the reed motion links upwardly to the point at which the toggle 17 is at least in the dead center position, the movement of the toggle past the dead center position into the locking position being accomplished by the spring 19. With the reed motion links in the uppermost position, as the lay 10 swings forwardly, the reed 11 will be kept locked in the forward position, since the links of the toggle 17 cannot break downwardly past the dead center position.

45 When it is desired to merely lay the picks into the cloth without beating them up, the reed motion shaft is rotated to the position shown in FIG. 3, in which the reed motion cranks do not raise the reed motion links up-

wardly, but rather hold them in a lowered position as compared to the FIG. 2 position. With the center pivot 18 of the toggle 17 thus held, when the lay moves forward, the toggle 17 will be broken downwardly, and since the breaking of the toggle shortens its length, the bottom of the reed will be swung back away from the fell of the cloth, counterclockwise in the figures. With the reed in this position, the picks will not be beat up into the fell of the cloth, so that after a certain number of picks and a letting off of the loop pile yarns, beating up can be carried out and the loop pile will be formed.

The description thus far is of a linkage for carrying out a reed motion which must be carried out on all terry looms. Inasmuch as the linkage is only typical, it will be understood that other similar linkages can be and are used, the common feature of all of them being that the toggle portion is pivoted at the center thereof and has the reed motion link 23 pivoted to the center thereof. It will be readily apparent to those in the art that any other common linkage which can be broken so as to swing the reed back away from the fell of the cloth and which can be locked to keep the reed from swinging back so that it moves forward into the beat up position when the lay moves forward can be used. It will also be understood that the reverse of such a linkage could be used, in which the straight line position of the linkage would swing the reed back and the broken position would hold the reed forward, could also be used. All of these linkages are broken or held in position by the raising and lowering of the reed motion link 23 under the action of the reed motion crank.

The present invention is directed to an especially simple means for controlling the rotation of the reed motion shaft 20 so as to stop the reed motion cranks 22 in either of the two positions in which the reed motion link 23 prevents the linkage from breaking or causes the linkage to break. The reed motion shaft 20 is driven from conventional loom drive means (not shown) which rotates it back and forth about its longitudinal axis between a first rotational position and a second rotational position. In the second rotational position the reed motion cranks 22 are in the position shown in FIG. 2, while in the first rotational position the reed motion cranks 22 are in position which is spaced clockwise from the position of the reed motion crank 22 shown in FIG. 3. The said conventional drive means is coupled to the reed motion shaft by a connection which permits the drive means to continue its motion even though the motion of the shaft is blocked. Such connections are well known and accordingly the connection is not described here in detail.

As seen in detail in FIG. 4, there is a reed motion adjusting arm 24 secured on the reed motion shaft 20 near the center thereof by means of set screws 24b, so that it can be adjusted lengthwise or rotationally of the shaft 20. Threaded through the free end of the reed motion adjusting arm 24 is an adjusting screw 24a.

Extending laterally from a point adjacent the path of movement of the free end of the adjusting arm 24 is a tubular member 25 mounted on loom frame members 26 by means of brackets 27. Slidably mounted within the tubular member 25 is a reed motion control rod 28 which has thereon a projection 29 to which is connected a spring 30 attached to loom frame member 31 and biasing the control rod 28 toward the path of the end of the adjusting arm 24. Projection 29 projects through an aperture 25a and the extreme end position of the rod 28 is established by the projection 29 abutting the end of the aperture 25a. This extreme end position of the rod 28 is a position in which the end of the rod lies in the path of the free end of the adjusting arm 24. The end of the rod 28 in the embodiment shown has a flat 28a milled thereon against which the adjusting screw 24a is abuttable.

On the end of the control rod 28 opposite the end

which is abutted by the set screw 24a is a loop 28b to which an actuating means is connected for moving the rod 28 within the tube against the action of the spring 30 to move the milled end out of the path of the free end of the adjusting arm 24. The actuating means shown in the drawings comprises a wire 32 the other end of which is connected to one arm 33a of a crank 33 pivotally mounted on a bracket 34 on one of the frame members 26. The other arm 33b of the crank has a chain 35 attached to the end thereof, and the other end of the chain 35 is connected to the free end of an arm fixed on the loop pile warp left-off shaft (not shown). In addition, the arm 33a has connected thereto a wire 36 the other end of which is connected to an arm 37 on a shaft 38 which is actuated by a loom control head, such as a box chain head, a dobby head, or a Jacquard head (not shown).

A cycle of the operation of the means for controlling the rotation of the reed motion shaft 20 commences with the reed motion shaft in the said second rotational position with the reed motion cranks 22 in the position shown in FIG. 2 in which beat up occurs. Thereafter, when the lay swings back, the reed motion control shaft 20 is rotated to the first position and then back toward the second position by the drive means. At this point, the shuttle 25 lays a pick into the cloth, and the lay again moves forward. The control rod 28 is allowed to move into the path of arm 24 under the action of spring 30 either by the action of the pile warp let-off shaft, which is rotated to a position in which the loop pile is not let off, or by the action of the control head. The lateral movement of the control rod 28 moves the milled end thereof into the path of the free end of the adjusting arm 24, whereupon the adjusting screw 24a abuts the milled flat 28a and the reed motion shaft is blocked. Since the reed motion shaft 20 has swung to the first position the reed motion link 23 has been lowered to the FIG. 3 position, and the toggle 17 is broken, thereby swinging the reed back away from the fell of the cloth, so that no beat up occurs. As the lay swings back the toggle will again be closed due to the relative movement between the lay and link 23.

On the next pick, the same action is repeated, the control rod 28 being left in the path of the adjusting arm 24, so that upon forward movement of the lay, the link 23 is prevented from rising, the toggle 17 is broken, and the reed is swung back. On the third pick, however, the control rod 28 is pulled laterally against the action of spring 30 out of the path of the adjusting arm 24. When the reed motion shaft 20 is rotated the arm will swing past the rod 28, so there will be nothing blocking further rotation of the shaft 20. The link 23 will be raised as the lay moves forward, and the toggle 17 will not be broken, so that the reed will be moved forward with the lay and will beat up the picks into the fell of the cloth, as in FIG. 2. This completes the cycle, and with the movement of the lay and reed back away from the beat up position, a new three pick cycle begins.

From this description, it will be clear to those skilled in the art how this simple control mechanism can be used to adjust the reed swing and vary the cycle easily and quickly. In order to adjust the swing of the reed, it is only necessary to adjust the adjusting screw 24a, since this will determine wherein relation to the position of the end of control rod 28 the adjusting arm 24 is stopped, and consequently will determine the vertical position of link 23. This in turn controls the amount by which the toggle breaks, so that if it is desired to have the reed swing back a little more, the adjusting screw 24a is screwed further through the arm 24, so that the FIG. 3 position of the link 23 is lower, causing the toggle to break further. If it is desired to cause a little less swing of the reed, the adjusting screw 24a is backed off, raising the FIG. 3 position of the link 23. If it is desired to have the reed swing back only part of the full swing, the link 23 can be caused to move to a higher position in FIG. 3. This will cause the toggle 17 to close part

way during the forward movement of the lay so that the swing of the reed will not be to the rearmost position shown in FIG. 3, but will be somewhere between the FIG. 2 and the FIG. 3 positions. This will cause partial beat up of the picks laid into the cloth, which is necessary when it is desired that all the pile loops project to the same side of the cloth. To do this, the control head is set so that it will withdraw the rod 28 part way on the pick after which it is desired to cause partial beat up. The end of the rod 28 is provided with a more deeply milled flat, for example a flat which has been milled through the longitudinal axis of the shaft, so that the adjusting arm 24 will be blocked in its movement at a point past the point at which it would be blocked for the full swinging back of the reed. The crank 22 will thus swing further and raise the link 23 higher, so that the toggle will not be fully broken when the lay moves forward. The reed will thus partially beat up the picks which have been laid in the cloth since the last full beat up.

It is very simple to change to regular weaving in which beat up occurs on every pick, or to change the number of picks which are laid into the cloth prior to beat up. All that is necessary is to change the control head so that the rod 28 is withdrawn from the path of arm 24 on every pick, or on every fourth, fifth, etc. pick. No new rod 28 is necessary, nor need the drive of the loom be changed in any way, except insofar as the control head and the pile let off is concerned.

The mechanism is extremely simple and easy to make and maintain, the parts consisting of a rod and a tube, together with the spring and the control linkages. Replacement of the adjusting screw 24a takes but a few seconds, and if it is desired to get a different reed motion, it is but a matter of minutes to change the rod 28. The mechanism is light in weight, and none of the parts are subject to hard wear.

It will of course be appreciated that if the toggle mechanism on the reed breaks in the upward direction, it will be necessary either to place the control rod above the arm 24 if the arm 24 is to project toward the front of the loom, or to place it behind the reed motion shaft 20 if it is desired to mount the rod 28 below the level of the shaft 20. This is because it will then be the lowering of the link 23 which is necessary to lock the toggle to cause the reed to beat up, thereby necessitating the rearrangement of the position of the control rod.

It will also be appreciated that the specific shape of the control rod need not be round. Other cross sectional shapes will be equally satisfactory, and for certain purposes might be preferred. The essential requirement is that the member against which the free end of the adjusting arm abuts be movable laterally of the movement of the adjusting arm, so that it can be withdrawn partially or completely so that different levels of flats can be placed in position in the path of the adjusting arm 24 easily and simply.

A further feature of the reed motion control according to the present invention is the combination therewith of a center reed lock motion. As seen best in FIGS. 5 and 6, a form of center reed lock which is common on wide looms, comprises a lock plunger 40 which is inserted into an aperture 41a in an aperture forming member 41 on the back of the reed bed 12 when the reed reaches the beat up position in order to prevent the reed from bowing away from the fell of the cloth in the center of the reed. The lock plunger 40 is mounted on a plate member 42 which is slideable up and down on a pin 43 which is mounted on a part 44 of the loom frame and which extends through an elongated slot 42a in the plate member. A spring 45 extends between the top of the frame part 44 to the bottom of the plate member 42 and tends to urge the plate member and the lock plunger 40 upwardly.

Center reed lock control means are connected to the

plate member 42 and to the reed motion control which controls the vertical reciprocating movement of the lock member 40. This means comprises a flexible strap 46 having a hook 47 on one end thereof hooked to the plate member 42, and having the other end extending around a pulley 48 mounted on a frame member 49 of the loom. The other end of the flexible strap 46 has a strap bracket 50 thereon and a strap bracket stud 51 is connected between the adjusting arm 24 of the reed motion control and the strap bracket 50.

During the operation of the loom, as the adjusting arm 24 swings upwardly in FIG. 4, to the position corresponding to the said first rotational position of the link 23 in FIG. 3, the end of the strap 46 connected to the stud 51 will be pulled upwardly so that the other end will be pulled downwardly, pulling the lock plunger downwardly against the action of spring 45. When the adjusting arm swings back, and abuts against the rod 28, so that the reed does not beat up, the end of the strap with the bracket 50 thereon will not be lowered very much and consequently the other end of the strap will not be raised very much. The lock plunger 40 will therefore not be allowed to rise into what would normally be a lay engaging position. However, when the rod 28 is withdrawn, and the adjusting arm 24 swings downwardly for the full extent of the rotational movement of control shaft 20, the end of the strap 46 with bracket 50 thereon will be lowered considerably, so that the other end will be allowed to rise under the action of spring 45 to enter into the aperture 41a on the back of the reed bed 12 to prevent the reed from bowing.

The same control which controls the reed motion is therefore utilized to control the center reed lock, the overall mechanism being extremely simple and easy to construct and maintain, yet replacing a vastly more complex and difficult to maintain apparatus.

It is thought that the invention and its advantages will be understood from the foregoing description and it is apparent that various changes may be made in the form, construction and arrangement of the parts without departing from the spirit and scope of the invention or sacrificing its material advantages, the form hereinbefore described and illustrated in the drawings being merely a preferred embodiment thereof.

I claim:

1. A reed motion control for a terry loom which has a reed swinging means for swinging the reed away from the beat up position and holding the reed in the beat up position, a reed motion shaft linked to the swinging means, and drive means for rotating the reed motion shaft back and forth between a position in which the reed swinging means holds the reed in the beat up position and a position in which the reed motion shaft is rotated beyond the position in which the reed swinging means is held out of the reed beat up position, said reed motion control comprising an adjusting arm adapted to be mounted on the reed motion shaft, a replaceable adjustable member on the free end of said adjusting arm adjustable in the direction of movement of said adjusting arm, a control member mounted for lateral movement relative to the path of said adjusting arm as it is swung back and forth by the reed motion shaft from a position in which one end is in the path of and abuttable by said adjustable member on said adjusting arm to a second position in which the end is out of the path of the adjusting arm, and actuating means connected to said control member adapted to couple said control member to a control means for the loom.

2. A reed motion control as claimed in claim 1 in which said replaceable adjustable member is a setscrew extending through the end of said adjusting arm.

3. A reed motion control for a terry loom which has a reed swinging means for swinging the reed away from the beat up position and holding the reed in the beat up position, a reed motion shaft linked to the swinging

means, and drive means for rotating the reed motion shaft back and forth between a position in which the reed swinging means holds the reed in the beat up position and a position in which the reed motion shaft is rotated beyond the position in which the reed swinging means is held out of the reed beat up position, said reed motion control comprising an adjusting arm adapted to be mounted on the reed motion shaft, a guide member mounted adjacent the path of said adjusting arm and extending laterally thereof, a control rod mounted in said guide member for lateral movement relative to the path of said adjusting arm as it is swung back and forth by the reed motion shaft from a position in which one end is in the path of and abuttable by said adjusting arm to a second position in which the end is out of the path of the adjusting arm, spring means coupled between said guide member and said control rod and urging said control rod toward the position in which the end is in the path of the adjusting arm, stop means on said guide member against which said control rod is abuttable limiting movement thereof toward the position in which the end is in the path of the adjusting arm, and actuating means connected to said control rod adapted to couple said control rod to a control means for the loom.

4. A reed motion control for a terry loom which has a reed swinging means for swinging the reed away from the beat up position and holding the reed in the beat up position, a reed motion shaft linked to the swinging means, and drive means for rotating the reed motion shaft back and forth between a position in which the reed swinging means holds the reed in the beat up position and a position in which the reed motion shaft is rotated beyond the position in which the reed swinging means is held out of the reed beat up position, said reed motion control comprising an adjusting arm adapted to be mounted on the reed motion shaft, a tubular member adapted to be mounted on the loom and extending laterally relative to the path of said adjusting arm as it is swung back and forth by the reed motion shaft, a control rod slidably mounted in said tubular member, said tubular member having an aperture therein and said control rod having a projection thereon extending through said aperture, said projection being movable in said aperture for permitting sliding movement of said control rod from a position in which one end is in the path of and abuttable by said adjusting arm to a second position in which the end is out of the path of the adjusting arm, a spring connected to said projection urging said control rod toward the position in which the end is in the path of the adjusting arm, and actuating means connected to said control rod adapted to couple said control rod to a control means for the loom.

5. A reed motion control as claimed in claim 4 in which said adjusting arm has a set screw threaded through the free end thereof which abuts the end of the control rod.

6. A reed motion control as claimed in claim 4 in which the end of said control rod which is abuttable by said adjusting arm has at least one flat thereon which is abutted by said adjusting arm.

7. A reed motion and center reed lock control for a terry loom which has a reed swinging means for swinging the reed away from the beat up position and holding the reed in the beat up position, a reed motion shaft linked to the swinging means, drive means for rotating the reed

motion shaft back and forth between a position in which the reed swinging means holds the reed in the beat up position and a position in which the reed motion shaft is rotated beyond the position in which the reed swinging means is held out of the reed beat up position, and a center reed lock having a lock plunger movable into and out of position behind the reed when the reed is in the beat up position to keep the reed from bowing, the lock plunger being spring biased toward the locking position said reed motion and center reed lock control comprising an adjusting arm adapted to be mounted on the reed motion shaft, a control member mounted for lateral movement relative to the path of the said adjusting arm as it is swung back and forth by the reed motion shaft from a position in which one end is in the path of and abuttable by said adjusting arm to a second position in which the end is out of the path of the adjusting arm, actuating means connected to said control member adapted to couple said control member to a control means for the loom, a flexible member adapted to have one end connected to the lock plunger of the center reed lock, and a connection between the other end of said flexible member and said adjusting arm for causing the lock plunger to be pulled downwardly and held down against the biasing thereof when said adjusting arm abuts said control member and allowing the lock plunger to move into the locking position when said adjusting arm moves past said control member.

8. A reed motion and center reed lock control as claimed in claim 7 in which said flexible member is a flexible strap and said connection between the said flexible member and said adjusting arm comprises a stud on said adjusting arm moving in the path of movement of said adjusting arm, the free end of said stud being connected to the end of said flexible strap.

9. A reed motion and center reed lock control as claimed in claim 8 in which said adjusting arm moves up and down in a vertical plane and in which it is blocked by said control member in a position just below the uppermost position of said adjusting arm, and said center reed lock control further comprises a pulley below the level of said adjusting arm around which said flexible strap runs, whereby restraining of the end of the strap connected to the said adjusting arm in an upper position holds the lock plunger in a lowermost position, and allowing the end of the strap connected to the adjusting arm to move downwardly when the adjusting arm does not abut the control member allows the lock plunger to move upwardly.
